UNITED STATES PATENT OFFICE

WILLIAM I. SILVERSTEIN, OF BROOKLYN, NEW YORK

MILITARY CAP

Application filed February 4, 1930. Serial No. 425,730.

This invention relates to caps and particularly to what might be termed military caps; and the object of the invention is to provide means for ventilating caps of the class specified in such manner as to render the ventilating means substantially concealed when the cap is in use; a further object being to provide means for closing the ventilating portion or area thereof, said means constituting 10 the usual finishing strip or chin strap employed in caps of the class specified; a further object being to provide the front end portion of the head encircling band of a cap with a plurality of vents or passages formed 15 in a reinforcing or stiffening member employed in the construction of the head encircling band of the cap; and with these and other objects in view, the invention consists in a cap of the class and for the purpose specified which is simple in construction, efficient 20 in use, and which is constructed as herein-after described and claimed.

The invention is fully disclosed in the following specification, of which the accompanying drawing forms a part, in which the separate parts of my improvement are designated by suitable reference characters in each of the views, and in which:

Fig. 1 is a side view of a cap made according to my invention with parts of the construction broken away.

Fig. 2 is an enlarged sectional, detail view through the front end portion of the head encircling band of the cap; and,

Fig. 3 is a partial section on the line 3—3 of Fig. 1.

For the purpose of illustrating one use of my invention, I have shown in Fig. 1 of the drawings, a military cap consisting of a head encircling band portion 5 at one end of which is arranged a forwardly and downwardly inclined peak 6 and to the upper end of which is attached a crown 7, the diameter of which is greater than that of the band 5, the forward end 7a of the crown being inclined up-

wardly as seen at 7b and the top of the crown being relatively flat as in other caps of this class.

Arranged within the head encircling band 5 is an annular reinforcing or stiffening strip 8 preferably composed of openwork material to render the same light in weight and also to provide a ventilator for the cap as later described. The strip 8 in the construction shown consists of a woven body of straw, reed or similar material which is so fashioned as to form comparatively large openings 8a therein as indicated in Fig. 1 of the drawings. The strip 8 is attached to the upper and lower ends of the band 5 in order to render said band substantially stiff and to maintain the same in upright position, and yet permitting the flexure thereof.

Arranged within the strip 8 is a sweat band 9 which is attached to the lower edge of the band 5 and the sweat band 9 is provided at the front end portion of the cap with a plurality of circumferentially spaced vent apertures 9a arranged in alinement with the apertures or openings 8a formed in the strip 8 and also in alinement with an elongated opening 5a formed in the front lower portion of the band 5 and which extends from the point x to the point x2 of said band as seen in Fig. 3 of the drawing. The ends x—x2 terminate short of buttons or other devices 10 attached to the side portions of the band 5 for securing strap members 11 and 12 to said band.

The free end of each strap member 11 and 12 is provided with a guide loop 11a—12a through which the other strap member is free to pass and said loops have projecting finger pieces 11b and 12b by means of which the separate members 11 and 12 may be properly adjusted upon the band 5 of the cap to arrange the same snugly thereon, the width of the strap members 11 and 12 being such as to completely cover the opening or aperture 5a in said band.

When the cap is used in normal temperature or in cold or cool weather, the strap members will be arranged snugly upon the band 5 and act as closures for the opening 5a. However, in hot weather or when the temperature is such as to cause the wearer to sweat, the strap members 11 and 12 may be separated to a slight extent in the manner seen in the several figures of the drawing so as to permit the passage of air in back of said strap members through the openwork strip 8 and the openings 9a in the sweat band to ventilate the cap and thus reduce excessive heating of the head.

It is to be noted that the slight extension of the strap members will not expose the ventilating aperture except by close inspection, thus maintaining a neat and finished appearance which is desired for military purposes. However, for practical purposes and when the question of appearance is not important, it will be understood that the strap members 11 and 12 may rest upon the upper part of the band 5 and be secured thereto by firmly drawing the loop ends to apply pressure of the strap members on said band or the strap members may be separated to a greater degree and allowed to rest upon the peak 6 of the cap or the band may be extended and placed beneath the chin or passed around the rear portion of the band 5 if desired.

It will be understood that while I have shown certain details of construction for carrying my invention into effect and have illustrated my invention as applied to a cap of specific structure, that my invention is not necessarily limited in these respects and various other changes in and modifications of the construction herein shown and described may be made within the scope of the appended claims without departing from the spirit of my invention or sacrificing its advantages.

Having fully described my invention, what I claim as new and desire to secure by Letters Patent, is:

1. A cap of the class described, the head encircling band of which is provided at the front end thereof with an elongated and circumferentially arranged opening, the sweat band of the cap having an opening registering with the opening in said band, means attached to said head encircling band and arranged outwardly thereof and normally forming a closure for said opening, and said last named means comprising an extensible strap provided with means for adjusting the spacing of the strap from the body of the hat to permit varying amounts of air to be transmitted therethrough.

2. A cap of the class described, the head encircling band of which is provided at the front end thereof with an elongated and circumferentially arranged opening, the sweat band of the cap having an opening registering with the opening in said band, means at-

tached to said head encircling band and arranged outwardly thereof and normally forming a closure for said opening, said last named means comprising an extensible strap provided with means for adjusting the spacing of the strap from the body of the hat to permit varying amounts of air to be transmitted therethrough, and a stiffening strip of openwork material arranged between the outer facing of the head encircling band and said sweat band. 70 75

3. A cap of the class described, the head encircling band of which is provided with an elongated vent opening arranged adjacent the front lower edge thereof and extending continuously to the front sides of said band, means mounted on the outer face of said band and adjustable toward and from the same normally forming a closure for said opening and a body of relatively stiff openwork material arranged upon and attached to the inner surface of the band adjacent said vent opening for supporting opposed walls of the opening in spaced relation with respect to each other. 80 85 90

4. A cap of the class described, the head encircling band of which is provided with an elongated vent opening arranged adjacent the front lower edge thereof and extending continuously to the front sides of said band, means mounted on the outer face of said band normally forming a closure for said opening and a body of relatively stiff, openwork material arranged upon and attached to the inner surface of the band adjacent said vent opening for supporting opposed walls of the opening in spaced relation with respect to each other, and said closure means involving an extensible strap for adjusting the spacing thereof with respect to said band to control the amount of air passed through said vent opening. 95 100 105

5. A cap of the class described, the head encircling band of which is provided with an elongated vent opening arranged adjacent the front lower edge thereof and extending continuously to the front sides of said band, means mounted on the outer face of said band and adjustable toward and from the same normally forming a closure for said opening and a body of relatively stiff openwork material arranged upon and attached to the inner surface of the band adjacent said vent opening for supporting opposed walls of the opening in spaced relation with respect to each other, and a sweat band attached to the lower edge of said first named band and arranged inwardly of said body of openwork material, said sweat band having apertures adapted to register with the openings in said band and body. 110 115 120 125

6. The combination with a peak cap of the class described, the head encircling band of which is provided with an adjustably extensible strap arranged externally of said band 130

at the front and front sides thereof and above
said peak, of a vent opening formed in said
band inwardly of and normally closed by said
strap whereby the adjustment of said strap
5 with respect to said band will control the
transmission of air through said vent open-
ing.

In testimony that I claim the foregoing as
my invention I have signed my name this 11th
10 day of December, 1929.

WILLIAM I. SILVERSTEIN.
